UNITED STATES PATENT OFFICE

140,428

DESIGN FOR A MOTION PICTURE FILM GATE

Otto R. Nemeth, Chicago, Ill., assignor to Products Development, Inc., Chicago, Ill., a corporation of Illinois

Application December 23, 1944, Serial No. 117,051

Term of patent 14 years

(Cl. D61—1)

To all whom it may concern:

Be it known that I, Otto R. Nemeth, a National of Czechoslovakia, residing at Chicago, in the county of Cook and State of Illinois, have invented a new, original, and ornamental Design for a Motion Picture Film Gate, of which the following is a specification, reference being had to the accompanying drawings, forming part thereof.

Figure 1 is a front elevational view of a motion picture film gate embodying the features of my design.

Fig. 2 is a side elevational view of the film gate. Fig. 3 is a top plan view of the film gate.

I claim:

The ornamental design for a motion picture film gate, substantially as shown.

OTTO R. NEMETH.
